UNITED STATES PATENT OFFICE.

LOUIS S. ROSS, OF NEWTONVILLE, MASSACHUSETTS, ASSIGNOR TO CENTRAL RAILWAY SIGNAL COMPANY, OF PITTSBURGH, PENNSYLVANIA, A CORPORATION OF NEW JERSEY.

SPIKE ATTACHMENT FOR RAILWAY SIGNAL-FUSEES.

1,296,561.

Specification of Letters Patent.

Patented Mar. 4, 1919.

Application filed November 29, 1918. Serial No. 264,573.

To all whom it may concern:

Be it known that I, LOUIS S. ROSS, a citizen of the United States, residing at Newtonville, in the county of Middlesex and State of Massachusetts, have invented certain new and useful Improvements in Spike Attachments for Railway Signal-Fusees, of which the following is a specification, reference being had therein to the accompanying drawing.

My invention relates to improvements in spike attachments for railway signal fusees, and the object of the present invention is to prevent a waste of the chemical compound within the fusee tube that is required by the method now in use of attaching the spike to the fusee tube.

Railway signal fusees primarily consist of a paper tube filled with a chemical, and one end of the tube fitted with a lighting head and the other end of the tube fitted with a spike for holding the fusee in an upright position by forcing the spike into a railroad tie or into the railroad bed.

In the manufacture of these fusees, the paper tubes are supported in groups within a suitable machine with the lighting end downward, and the chemical compound is placed in these tubes in measured quantities or "charges", each quantity or charge being packed by a suitable plunger carried by the machine until the tube is filled with the compound.

The manner of now connecting the spike to the fusee, consists in providing a plug (wood or metal) carrying a spike, which plug will snugly fit within the fusee tube and about an inch in length. In order to insert the plug within the fusee tube, it is necessary to remove the chemical compound from the plug end of the tube a depth sufficient to receive the plug, which is usually about an inch, and this is done by boring or drilling the compound from the tube to the necessary depth. The plug is then inserted within the tube and either cemented or tacked therein. This is the method that is universally practised for attaching spikes to fusees and has been for a great many years. In the practice of this method, there is a waste of the chemical compound which is removed from the tube and it amounts to an enormous quantity in a fusee factory

where hundreds of thousands of fusees are constructed.

Railway signal fusees and, as a consequence, their tubes are made of various lengths, ranging, for instance, from five to fourteen inches and, therefore, the amount of waste varies from one-fifth to one-fourteenth of the whole quantity used in the manufacture of the fusee, which is a very large percentage and runs into a large amount of money to the manufacturer.

It is well-known to those skilled in the art that railway signal fusees are constructed to burn predetermined periods of time, that is to say, usually five or ten minute fusees, though the time of burning may vary and, therefore, the length of the fusee usually varies according to the time it is to burn.

In carrying out my present improvement, I so construct the spike attachment that it is not necessary to remove any part of the chemical compound from the fusee tube and, as a consequence, the fusee and tube may be made an inch shorter for burning a specified time than is now required, and there is a saving of that part of the compound which must now be removed from the fusee tube in the method of manufacturing them, in order to accommodate the fusee plug that is placed therein. This plug must be of sufficient length to give proper holding stability within the tube to withstand the lateral strain of the blow when the fusee is thrown to cause the spike to enter either a railway tie or the bed of the railroad, and the length of the plug required to meet these conditions has been found to be about an inch in length.

In addition to the saving of the chemical compound which varies from one-fourteenth to one-fifth of the whole amount, as heretofore stated, my improvement avoids the operation and, therefore, the cost of removing the compound from the end of the tube which, however, is very slight in cost as compared to the value of the wasted compound.

Referring now to the drawings—

Figure 1 is a perspective view partly in section, showing my improved spike attachment applied to a fusee.

Fig. 2 is a partial longitudinal central sec-

tional view of a fusee tube and of my improved spike attachment, the parts shown in separated relation.

Fig. 3 is a longitudinal central sectional tube showing my improved spike attachment applied to the fusee tube.

Fig. 4 is a longitudinal sectional view showing a modified form of plug and means of attachment embodying my present improvement.

Figs. 5, 6, 7, 8, 9, 10 and 11, each shows modified forms of spike attachment which embody my present improvement.

In the practice of my present improvement, the fusee tube 1 will be made about an inch shorter than the fusee tube now provided for a fusee to burn a certain predetermined period of time, and this tube is filled with a chemical compound 2, in a suitable machine, as heretofore described, the tube being filled with the lighting end 3 down, as shown in Fig. 2.

My present improvement comprises a cap 4, adapted to fit outside of the spike end of the fusee tube 1, and this cap carries a spike 5. In the form shown in Figs. 1, 2 and 3, the cap is provided with a shallow wood plug 6, suitably fastened within the closed end of the cap and through which the spike passes. The cap is in this form fastened to the tube by a suitable cement 7, preferably of a water-proof character.

My spike carrying cap is no more expensive than the usual plug carrying spike, and it preferably consists of a unitary structure to be applied to the fusee tube, though the spike with the shallow plug 6 may be placed in position on the tube and the cap placed thereover, but that would mean additional care and time in applying the improvement as compared with having it as a unitary structure.

In Fig. 4, the cap 4^a is made dome-shaped and the plug portion 6^a is made of a corresponding shape to fit the cap. As shown in this figure, the cap is secured to the fusee by means of suitable tacks 8, which are driven through the cap and the tube into the chemical compound.

When the chemical compound is placed within the fusee tube, it is in a granular or powder condition, but after it stands for a time it solidifies and becomes sufficiently solid to prevent the head 9 of the spike from being driven into the composition by the blow caused when driving the spike into the object for sustaining the fusee in an upright position.

The chemical compound being in a granular or powder form when it is packed into the tube 1, and the plug end of the fusee being the filling end of the tube, the compound in the inlet or spike end of the fusee is less tightly packed than in other portions

of the fusee, because it has received less packing blows, and as a consequence at the filling end for, at least a short distance, the compound is loose until it has stood sufficiently long to become solidified. If the spike plug is applied to the fusee, before the filling has become hardened, the construction thereof may be slightly modified as shown in Fig. 5. In this modification the plug has a tapered flange 10, which will partially enter the compound before it has hardened. This modification is within the scope of my present improvement, because it avoids the necessity of removing any of the compound, which is the primary object of my present improvement.

Fig. 6 shows the same construction as Fig. 5, except that the cap is held in position by tacks 8^a, instead of by cement as in Fig. 5.

In Fig. 7, the plug 6^c is composed of the form of plug shown in Figs. 3 and 5, in that it has the tapered flange 10^a of Fig. 5, and the portion 10^b which projects over the end of the fusee tube 1. Also in this Fig. 7, the cap 4^b is secured to the tube 1 by crimping the cap and the fusee tube, as shown at 11.

In this Fig. 7, also the cap 4^b is an open ended tube and the plug 6^c is constructed to form the closed end of the cap.

In Fig. 8, I have shown a metal cap 12, and in this case the head 9 of the spike 5 is fastened to the cap by crimping the cap around the head of the spike, as shown at 13, and in this figure the metal cap 12 is secured to the tube 1, by indented portions 14, so shaped that the cap can be forced on the tube, but cannot be pulled from it.

Fig. 9 is another slight modification embodying my improvement, in that the cap plug 15 is made of such a size that it can be forced slightly into the end of the fusee tube 1, as shown at 16, when the cap is applied to the fusee before the compound 2 at the plug end has become hardened. In this figure the cap is shown attached to the fusee by means of tacks 17.

Fig. 10 shows a cap constructed like that shown in Fig. 5, and differs from Fig. 5 only in the manner of attaching the cap to the fusee tube by making indentations in the cap and tube, as shown at 18.

Fig. 11, shows a form of cap and plug, the same as that shown in Fig. 9, but shows the cap attached to the fusee by punches 19, which are made at an angle so that the cap cannot be pulled therefrom.

It will be observed from the several slight modifications of the cap and the cap plug, that in each instance it is applied to a fusee tube and is completely filled with the compound, or substantially completely filled with the compound at the time the cap is applied thereto, as distinguished from applying the spike carrying member to tube from

which an appreciable quantity of the compound has been removed to accommodate the spike attachment.

Having thus described my invention, 5 what I claim and desire to secure by Letters Patent is:

1. A railway signal fusee having a spike receiving end, comprising a tube, a burning composition therein, one end of the tube 10 substantially in the transverse plane of the compound at the spike end of the fusee, and a spike carrying member attached to said end of the tube and located substantially wholly outside of the tube, whereby waste 15 of the burning composition in the manufacture of the fusee is prevented.
2. The combination with a railway signal fusee tube having a burning compound therein evenly filling the tube at its 20 spike end, of a spike carrying cap applied to the outside of the filled end of the fusee tube.
3. The combination with a railway signal fusee tube substantially evenly filled with 25 a burning compound, of a cap having a spike carrying plug within its outer end, the cap applied and attached to the filled end of the fusee tube.
4. The combination with a railway signal fusee tube substantially evenly filled with a 30 burning compound, of a spike cap applied to the filled end of the fusee tube, the cap having therein a spike carrying plug with an inwardly projecting flange entering the compound at the filled end of the tube.
5. An improved railway signal fusee, 35 comprising a tube having an open filling

end, a quantity of compound to burn a predetermined time and substantially evenly filling the tube, and a spike carrying attachment applied to the open filled end of the tube.

6. An improved railway signal fusee, comprising a quantity of compound to burn a predetermined time, a fusee tube of a length to just hold the quantity of compound and having a filling end, and a spike carrying cap applied to the filled open end of the fusee tube.

7. A railway signal fusee comprising a tube, a burning composition substantially evenly filling the tube, and a spike carrying member comprising a plug, and a cap projecting beyond the plug and telescoping the outer surface of the tube and forming attaching means to the tube beyond and independent of the plug.

8. A railway signal fusee comprising a tube, a burning composition substantially evenly filling the spike end of the tube, and a spike attaching member comprising a cap, a spike carrying plug within the cap, the cap projecting beyond the plug a distance substantially equal to the length of the plug for the purpose of telescoping the fusee tube and forming an attachment to the tube for holding the spike plug thereto.

In testimony whereof I hereunto affix my signature in the presence of two witnesses.
